CLAIM

I claim the ornamental design for a collapsible cup, as shown and described.

DESCRIPTION

FIG. 1 is a top perspective view of a first embodiment of a collapsible cup in an expanded position.

FIG. 2 is a front elevation view of the first embodiment of the invention in the expanded position. The back elevation view of the first embodiment in the expanded position is a mirror image of FIG. 2.

FIG. 3 is a right side elevation view of the first embodiment of the invention in the expanded position.

FIG. 4 is a left side elevation view of the first embodiment of the invention in the expanded position.

FIG. 5 is a top plan view of the first embodiment of the invention in the expanded position.

FIG. 6 is a bottom plan view of the first embodiment of the invention in the expanded position.

FIG. 7 is a cross section view showing a section taken along line 7-7 of FIG. 5.

FIG. 8 is a top perspective view of the first embodiment of the invention in a collapsed position.

FIG. 9 is a front elevation view of the first embodiment of the invention in the collapsed position. The back elevation view of the first embodiment in a collapsed position is a mirror image of FIG. 9.

FIG. 10 is a right side elevation view of the first embodiment of the invention in the collapsed position.

FIG. 11 is a left side elevation view of the first embodiment of the invention in the collapsed position.

FIG. 12 is a top plan view of the first embodiment of the invention in the collapsed position.

FIG. 13 is a bottom plan view of the first embodiment of the invention in the collapsed position.

FIG. 14 is a cross section view showing a section taken along line 14-14 of FIG. 12.

FIG. 15 is a top perspective view of a second embodiment of the invention in an expanded position.

FIG. 16 is a front elevation view of the second embodiment of the invention in the expanded position. The back elevation view of the second embodiment in the expanded position is a mirror image of FIG. 16.

FIG. 17 is a right side elevation view of the second embodiment of the invention in the expanded position.

FIG. 18 is a left side elevation view of the second embodiment of the invention in the expanded position.

FIG. 19 is a top plan view of the second embodiment of the invention in the expanded position.

FIG. 20 is a bottom plan view of the second embodiment of the invention in the expanded position.

FIG. 21 is a cross section view showing a section taken along line 21-21 of FIG. 19.

FIG. 22 is a top perspective view of the second embodiment of the invention in a collapsed position.

FIG. 23 is a front elevation view of the second embodiment of the invention in the collapsed position. The back elevation view of the second embodiment in a collapsed position is a mirror image of FIG. 23.

FIG. 24 is a right side elevation view of the second embodiment of the invention in the collapsed position.

FIG. 25 is a left side elevation view of the second embodiment of the invention in the collapsed position.

FIG. 26 is a top plan view of the second embodiment of the invention in the collapsed position.

FIG. 27 is a bottom plan view of the second embodiment of the invention in the collapsed position; and,

FIG. 28 is a cross section view showing a section taken along line 28-28 of FIG. 26.

The diagonal shading using solid lines of varying darkness in the cross-sectional views indicate a cross-section.

The dashed lines depict portions of the collapsible cup or planes for sectional views that form no part of the claimed design.
